UNITED STATES PATENT OFFICE.

EMIL GATHMANN, OF NEW YORK, N. Y.

INGOT-MOLD.

974,133.

Specification of Letters Patent.

Patented Nov. 1, 1910.

Application filed June 30, 1910. Serial No. 569,731.

To all whom it may concern:

Be it known that I, EMIL GATHMANN, a citizen of the United States, residing in the city, county, and State of New York, have 5 invented certain new and useful Improvements in Ingot-Molds, of which the following is a specification.

My invention relates particularly to molds for casting steel ingots, but it may be used 10 in connection with molds of other kinds.

In my U. S. Patents No. 921,972 of May 18, 1909 and No. 940,386 of November 16, 1909, I have shown molds for casting steel ingots in which provision is made for accelerating heat radiation and thus favoring 15 the cooling of the molten mass to a greater extent at the bottom and lower part of the mold than at the upper part thereof, which upper part is provided with means for conserving the heat of the adjacent molten mass 20 within the mold. By those improvements the formation of pipes and blow holes in the ingot was greatly reduced.

According to my present invention I have 25 provided a new way of conserving the heat in the upper part of the ingot and of accelerating the absorption or radiation of heat in the lower part thereof. This I accomplish by giving to the mold chamber a tapering 30 formation from the bottom or base thereof upward and outward to the base of the neck of the mold, and a reverse taper, *i. e.*, an inward and upward taper from the base of the neck to the top thereof. By this construction, the molten metal as it shrinks will 35 remain in close contact with the lower part of the mold while the upper part of the molten ingot will shrink away from the walls of the ingot and thus an insulating air space 40 will be produced which will assist in conserving the heat of the ingot in its upper portion.

In the accompanying drawings, Figure 1 shows a vertical central section through an 45 ingot mold embodying my improvements with an ingot therein. Fig. 2 shows a transverse section on the line 2—2 of Fig. 1. Fig. 3 shows a modified way of forming the lower portion of the mold.

The mold is divided vertically into two 50 sections A, and A' which have an interlocking connection with each other as shown in Fig. 2. Any suitable devices may be employed for holding the sections in place, such 55 devices being well known in this art and

are not illustrated. The mold sections may rest on a stool C or the base of the mold may be formed as indicated in Fig. 3. Except as to the shape of the mold chamber, the mold is similar to those shown in my former patents, *i. e.*, the lower part of the mold is constructed to favor heat radiation while the upper part or neck is reduced in thickness to conserve the heat of the ingot. Preferably, as shown in my former patents, the lower 65 portion of the mold is provided with ribs *a* which, as shown in Fig. 1, extend horizontally around the outside of the mold, but they may be otherwise arranged. The walls of the neck B are thinner than the walls of 70 the body of the mold for the purpose described in my former patents.

The heavier walls of the body of the mold prevent any material outward expansion and enlargement of the ingot mold chamber 75 as they remain comparatively cool and thus insure relatively close contact with the hot ingot walls, whereas the thinner walls of the necked-in upper portion B are heated 80 through and expand more readily thus enlarging the upper part of the ingot chamber and providing a relatively larger clearance or air space about the upper part of the hot ingot walls. The material of which the inner mold walls throughout their entire 85 length are constructed, is a metal such as cast iron which absorbs heat rapidly and expands considerably upon rise of temperature whereby a differential rate of expansion is obtained between the upper and 90 lower walls of the mold.

The mold chamber, as shown, is made to taper from its lower end upwardly and outwardly to the line *g*—*g* at the base of the neck and from this line it tapers upwardly and inwardly to the top of the neck. By this construction after the metal is teemed into the mold approximately 85% of the 95 ingot X during its shrinkage remains in close contact with the walls of the mold, while the upper part of the molten ingot as it shrinks draws away from the walls of the mold and thus an air space is formed 100 which materially assists in preventing the radiation of heat. The ratio of taper is preferably greater in the upper part of the mold than in the lower part thereof. I prefer to employ a taper in the upper inwardly inclined part of the mold walls of at least 105 three times as much taper per unit of verti- 110

cal height as the taper employed for the lower side walls of the mold so that the interval or air space between the ingot and the walls of the mold will increase considerably during the cooling of the ingot. As approximately 85% of the ingot remains in actual contact with the mold during the cooling or setting, the radiation of heat or the absorption of heat is materially promoted while the cooling of the upper part of the ingot is materially retarded by the surrounding film of air which, being rarefied, is a very poor conductor of heat.

In the case of ingots of large diameter or 15 those cast of alloys in which the sidewise shrinkage is excessive in order to insure close contact of the lower side walls of the ingot with the corresponding inner side walls of the retaining mold, I may construct the 20 stool C with a removable center piece C' which is adapted to be slightly lowered to compensate for the sidewise shrinkage, or if desired it may be constructed to be shifted sidewise or entirely removed soon after 25 the ingot has been cast while its central portion is still fluid but after its outer lower portion and side walls have been solidified. This lowering or shifting of the partly solidified ingot insures a good contact and 30 thus better heat transference to the mold of the lower portion of the ingot and at the same time increases the air film at the upper side walls of the ingot. Instead of lowering the central supporting portion of the 35 stool or shifting the same sidewise means may be employed to bodily raise the mold from the stool soon after teeming of the ingot and after its outer lower portions have solidified. This would give the same result, i. e., close, firm contact of the lower side walls of the ingot with the mold.

In place of the ribbing for the cooling of the lower side portions of the mold water spraying or induced or forced air currents 45 might be used to accelerate the cooling of this portion of the mold.

In my application for Patent No. 579,690, filed August 30, 1910, I have claimed a method of casting ingots consisting in pouring the molten metal into a mold, producing an air space between the upper inner walls of the mold and the upper part of the hot ingot while keeping the lower part of the ingot in close contact with the walls of the mold chamber while the solidification of the ingot is in progress.

I claim as my invention:

1. An ingot mold the upper part or neck of which retards the radiation of heat from the ingot to a greater extent than the lower part and the inner walls of which forming and defining the ingot chamber, taper upwardly and outwardly from its base, and then upwardly and inwardly toward its 65 top, the material forming said inner walls

of the mold being metallic both for the outwardly and inwardly tapered portions.

2. A longitudinally divided metal ingot mold the upper part or neck of which retards the radiation of heat from the ingot to a greater extent than the lower part and the inner walls of which forming and defining the ingot chamber taper upwardly and outwardly from its lower portion, and then upwardly and inwardly toward its upper portion, the said outwardly and inwardly tapered portions of the mold walls being integrally formed.

3. An upright metal ingot mold the upper part or neck of which retards the radiation of heat from the ingot to a greater extent than the lower part the inner walls of which forming and defining the ingot chamber taper upwardly and outwardly in its lower part and then upwardly and inwardly at its upper part, the taper of the said upwardly and inwardly inclined part being more than three times as great per unit of vertical height as the taper of the said lower inclining walls.

4. An upright metallic ingot mold the upper part or neck of which retards the radiation of heat from the ingot to a greater extent than the lower part the inner walls of which forming and defining the ingot chamber are formed by tapering side walls, the taper of the upper inwardly inclined part of the said inner walls being more than three times as great per unit of vertical height as the taper of the lower upwardly inclined side walls.

5. An ingot mold, the inner walls of which forming and defining the ingot chamber taper upwardly and outwardly from its base and then upwardly and inwardly relatively to the taper of the lower portion of the chamber, the walls of said chamber being thinner at the upper portion than at the lower portion thereof whereby said upper walls are made to expand more readily than the lower walls.

6. A metal mold which is provided with means for promoting heat absorption from the ingot, and the chamber of which tapers upwardly and outwardly from its base, and means at the upper end of said mold for conserving the heat of the upper part of the ingot and which has a chamber that tapers upwardly and inwardly relatively to the taper of the chamber in the lower part of the mold.

7. A metal mold for ingots provided with ribs for promoting heat absorption from the ingot, and the chamber of which tapers upwardly and outwardly from its base, means at the upper end of said mold for conserving the heat of the upper portion of the ingot and having a chamber which tapers upwardly and inwardly relatively to the taper of the chamber in the lower part

of the mold, in combination with means for lowering the ingot relatively to the mold after it has partially solidified.

8. A metal mold the lower part of which is provided on its exterior surface with ribs 5 to favor heat radiation while the upper part or neck is constructed to conserve heat, and the chamber of which mold tapers upwardly and outwardly from its base and then up- 10 wardly and inwardly to its top.

9. A metal mold the chamber of which tapers upwardly and outwardly in combination with a stool, the central portion 15 of which supporting the ingot is removable while the outer portion continues to support the mold.

10. A metal mold the chamber of which tapers upwardly and outwardly from its base and then upwardly and inwardly to 20 its top, in combination with a stool supporting the mold and ingot, the said stool having that portion which supports the ingot adjustable for independent movement while that portion which supports the mold 25 remains fixed.

11. A metal mold the chamber of which tapers upwardly and outwardly from its base and then upwardly and inwardly toward its top, in combination with a stool supporting the mold and the ingot, the said 30 mold having that portion which supports the side walls of the ingot adjustable for independent movement while the portion of the stool which supports the ingot remains fixed. 35

12. A metal mold the chamber of which tapers upwardly and outwardly from its base and then upwardly and inwardly to the top, in combination with a stool having an outer portion upon which the mold rests 40 and an inner portion upon which the ingot is adapted to at first rest but which is removable for the purpose of lowering the ingot in the mold while it is cooling.

In testimony whereof, I have hereunto 45 subscribed my name.

EMIL GATHMANN.
